AWNNG BRACKET

Edwin Mitchell, Warren Ohio, assignor to Walter A.
Curtze, Erie, Pa.

Application December 6, 1956, Serial No. 44,084

Term of patent 14 years

(Cl. D21—6)

FIG. 2

FIG. 1

Fig. 1 is a front elevational view of an awning bracket showing my new design; and

Fig. 2 is a top edge view thereof.

I claim:

The ornamental design for an awning bracket, substantially as shown.
